UNITED STATES PATENT OFFICE.

CARLISLE H. MIDDAUGH, OF LAWRENCEVILLE, PENNSYLVANIA.

SEPARATING-CASE.

1,030,317.

Specification of Letters Patent. Patented June 25, 1912.

Application filed October 26, 1911. Serial No. 356,908.

To all whom it may concern:

Be it known that I, CARLISLE H. MIDDAUGH, a citizen of the United States, residing at Lawrenceville, county of Tioga, 5 and State of Pennsylvania, have invented certain new and useful Improvements in Separating-Cases, fully described and represented in the following specification and the accompanying drawings, forming a part 10 of the same.

This invention relates to a separating device in which letters, cards, papers, &c., may be temporarily held in separate groups during a sorting operation.

15 The invention relates to a holder open at least upon the front side to receive the papers while sorting, and the invention includes partitions secured movably at their front ends upon a rod, and the rod provided with means for holding it adjustably and removably within the holder. The partitions are withdrawable from the front of the holder with the rod, to allow of quick and easy access to the papers when sorted, 25 the papers then remaining in the holder ready for bunching or tying. Instead of removing the papers from the front of the holder, they may be removed from the back by making the back of the holder open and 30 notching the rear ends of the partitions or cutting them short of the back, so that the papers can be grasped and withdrawn without moving the partitions. The holder is preferably mounted upon a pivot, so that 35 either the front or back can be turned to the operator. The holder may be used openly upon a desk, or set upon shelves in a cabinet in any desired number, or a shelf in a cabinet may be used as the bottom of 40 the holder, and the rod mounted removably near the front edge of the shelf to carry the partitions. In either case, grooves are made in the ends of the holder close to the bottom, to receive sliding bars which are 45 connected to the guide-rod carrying the partitions.

The invention also includes various details of construction, which will be understood by reference to the annexed drawings, 50 in which—

Figure 1 is a perspective view of a "separating case" complete; Fig. 2 is a plan of the guide-bar and partitions; Fig. 3 is an end view of the same; Fig. 4 is a transverse vertical section of a cabinet A⁴ with 55 five shelves, and doors hinged to the back

of four of the shelves; Fig. 5 is a perspective view of a table-top with three cabinets pivoted thereon; and Fig. 6 of a perspective view of a holder with the back 60 open to remove the paper from the rear side of the same.

In Fig. 1, the holder is shown with the bottom a, ends b, and back c, the ends having, close to the bottom, grooves d in which 65 sliding-bars e are fitted and connected rigidly at their outer ends to the guide-rod f. Blocks g are fitted movably upon the guide-rod, and the lower front corners of the partition h are attached to such blocks. The fronts of the blocks are provided with serial numbers i, as a designation for the group of papers next to each partition. The blocks may be provided with descriptive labels if preferred. By sliding 70 the bars e into the grooves d, the rod f is held at the front edge of the bottom a with the partitions extending backwardly therefrom and resting upon the bottom. As the blocks and their attached partitions are 75 movable upon the guide-rod, the partitions can be set at any distance from one another, or from the ends b of the holder, and the holder being entirely open upon the front, 80 the papers can be readily inserted between the partitions, and the partitions pressed close upon the papers, when it is desired to 85 group them together for removal.

If the holder be set upon a desk, the 90 papers can be removed from the open top, but if placed in a cabinet as shown in Figs. 4 and 5, any part of the papers can be 95 readily removed from the holder, by withdrawing the guide-rod and partitions. The removal of the papers can also be facilitated by making the back of the holder open, as shown in Fig. 6, and extending the partitions only two-thirds of the way backward, so that when placed between shelves in a cabinet, as in Figs. 4 and 5, with suitable 100 doors in the back of the cabinet, the papers can be removed from between the partitions without moving the guide-rod or partitions at all.

Doors D are shown hinged to the rear 105 edges of four of the shelves, and may be mounted upon spring hinges, such as are commonly used for such purposes, to hold the doors normally shut.

In Fig. 5, the cabinets A, A', and A² are 110 shown mounted upon a desk B, being mounted upon pivoted standards H by which the

back of any of the cabinets can be turned around for withdrawing the papers from the rear ends of the holders. In Fig. 5, three cabinets are shown with doors C, which are closed upon the cabinet A², and the cabinet A' is shown with grooves d' formed in its side-walls near the ends of the top shelf, whereby the guide-bar and partitions shown in Figs. 2 and 3 can be fitted directly between the shelves, without the intervention of the separate holder. (See Fig. 4.) In this case, the top-shelf of the cabinet forms the bottom of the holder and the side-walls of the cabinet form the ends of the holder, but the operation of the holder and of the partitions therein is exactly the same as with the separate holder shown in Fig. 1.

By extending the partitions only a part of the way backward in the holder within the cabinet, whether such holder be separate or formed upon the cabinet shelf, the papers when set between the partitions, in contact with the rear doors of the cabinet, project beyond the partitions, and can be easily grasped for removal when such rear doors are opened.

The guide-rod with its end-bars e, its movable blocks g and partitions h attached thereto, forms an attachment for filing-cabinets which can obviously be used with the separate holder shown in Fig. 1, or with the cabinet shelves having grooves d' near their ends, as in the cabinet A' in Fig. 5, and I have therefore made claim to such a cabinet attachment for separating and sorting papers.

The cabinets are shown with a vertical series of holders, with a variety of constructions embodied in the cabinet A to illustrate the different modes in which the holder or separator can be used in the cabinet. The top shelf in the cabinet A has grooves d' formed immediately above the shelf to receive the sliding-bars e, and the parts a and b are not, therefore, employed. Upon the remaining shelves of that cabinet, the separate holders are shown with bottom a and ends b, the holders upon three of the shelves being open at the back so that the 50 contents can be withdrawn from the rear by opening the doors D. The two lower spaces in the cabinet have completely separate holders with inclosed backs like that shown in Fig. 1, from which the papers can be removed from the front only. All of the 55 holders except that formed by the top shelf are removable from the cabinet with all their contents.

The partitions h are preferably formed of thin flexible elastic metal, which bends readily when bunching the papers together which have been assembled between the partitions, as when withdrawing them from the rear side of the holder.

65 It will be understood that the guide-rod

f which supports the partitions movably is located close to the bottom of the holder at the front edge of the same, so as not to interfere with the insertion of the papers from the front of the holder between the several partitions.

A holder open at the back is preferably mounted upon a pivoted standard H whether a single holder be used, as in Fig. 6, or a cabinet containing a collection of such holders, as in Fig. 5.

The movability of the rod f with the partitions not only permits them to be removed entirely from the holder but to be drawn partly forward whenever necessary, 80 to insert documents of unusual length between the partitions, it being understood that the papers, letters, circulars, or other matter to be sorted is in practice placed upon the bottom of the cabinet behind the 85 rod f, so that the rod prevents them from accidentally slipping out of the holder at the front.

This separating device is not designed for use as a permanent file, but for temporarily holding the papers, &c. during a sorting operation, at the end of which they would be removed. The structure is thus designed to accommodate itself to the sizes of the groups, by having the partitions 95 freely movable upon the guide-rod f, and to the length of the papers or documents by drawing the rod f forwardly to the required extent in the holder. The holder is thus adapted to a great variety of uses, and for such uses suitable labels may be affixed to the partitions in any manner and at any convenient point, whether at the top or bottom of the partition.

As the rod f offers a slight hindrance to 105 the removal of the papers at the front, I consider it preferable to make the holder open at the back and mount it so that the back can be turned to the operator whenever desired, to withdraw the sorted papers.

Having thus set forth the nature of the invention what is claimed herein is:

1. The combination, with a holder having ends provided with grooves, of bars fitted movably to the grooves, a guide-rod connecting the bars, and partitions having a movable connection with the guide-rod, whereby the rod and partitions can be simultaneously removed from the holder.

2. The combination, with a holder having ends provided with grooves, of bars fitted movably to the grooves, a guide-rod connecting the bars, and partitions having a movable connection with the guide-rod, such partitions being formed of a thin flexible 125 elastic metal to facilitate the removal of the papers.

3. The combination, with a holder having ends provided with grooves, of bars fitted movably to the grooves and connected by a 130

- guide-rod, blocks fitted movably to the guide-rod, and partitions attached to the blocks and projected therefrom between the bars.
- 5 4. The combination, with a cabinet having a vertical series of holders for papers with a door at the rear end of each holder, and each holder having grooves at the bottom of its ends, of bars fitted removably to the 10 grooves, a guide-rod connecting such bars and having blocks movable thereon and partitions attached thereto with space between the rear ends of such partitions and the rear doors of the cabinet, whereby the papers 15 can be grasped at the rear end without interference from the partitions when the rear doors are opened.
5. A cabinet having a series of holders, 20 guide-rods mounted removably at the front edge of each holder with partitions projected part way to the back of the cabinet, doors
- upon the front of the cabinet exposing all of the holders, and a series of doors at the back of the cabinet for exposing each holder separately.
- 25 6. A holder for sorting letters, papers, &c. having a bottom and ends provided with grooves and having back and front open, slide-bars fitted movably to the grooves, a guide-rod connecting the bars, partitions 30 having a movable connection with the guide-rod, and a pivot supporting the holder; whereby the front or rear of the holder may be turned to the operator at pleasure.
- In testimony whereof I have hereunto set 35 my hand in the presence of two subscribing witnesses.
